Primary Examiner — Steven J Czyz*Assistant Examiner* — Varun Salil Kamat(74) *Attorney, Agent, or Firm* — Chun-Ming Shih;
LANWAY IPR SERVICES(57) **CLAIM**

The ornamental design for a cabinet, as shown and described.

DESCRIPTION

FIG. 1 is a perspective view of a cabinet showing the new design;

FIG. 2 is another perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a perspective view thereof showing a door opened. The broken lines shown in the figures are for the purpose of illustrating portions of the cabinet and form no part of the claimed design.

1 Claim, 9 Drawing Sheets(56)
